UNITED STATES PATENT OFFICE.

LEWIS MOORE, OF JOLIET, ILLINOIS, ASSIGNOR TO MOORE BROTHERS COMPANY, OF JOLIET, ILLINOIS, A CORPORATION OF ILLINOIS.

COAL STOVE.

1,413,344.

Specification of Letters Patent. Patented Apr. 18, 1922.

Application filed March 26, 1920. Serial No. 368,886.

To all whom it may concern:

Be it known that I, LEWIS MOORE, a citizen of the United States, residing in Joliet, in the county of Will and State of Illinois, have invented a new and useful Improvement 5 in Coal Stoves, of which the following is a specification.

This invention relates in general to stoves and has more particular reference to coal 10 and wood stoves provided for air heating.

A principal object of the invention is the provision of a stove consisting of a minimum of readily assembled parts which will efficiently direct and heat a current of air passing 15 through the stove itself and in intimate contact with the heating surfaces.

Numerous other objects and advantages of the invention will be apparent as it is better understood from the following description 20 when considered in connection with the accompanying drawings illustrating a preferred embodiment thereof.

On the drawings,

Figure 1 is a perspective view of a stove 25 embodying my present invention;

Fig. 2 is a vertical section through the same;

Fig. 3, is a section taken substantially on the line 3—3 of Fig. 2;

Fig. 4 is a partial enlarged detail view 30 showing the relation and action of certain parts;

Fig. 5 is a perspective view showing the walls of the front part of the stove jacket disjoined;

Fig. 6 is an enlarged section of a corner of the jacket; and

Fig. 7 is a section taken substantially on the line 7—7 of Fig. 2.

The stove shown on the drawings 40 comprises in the present instance an ashpit 9, a fire-box 10, a dome 11 and a jacket. The ashpit is elevated upon a suitable supporting base 13 of any preferred or usual construction. The dome 11 and the fire-box 10 form 45 together a combustion chamber. The fire-box is provided with the usual grate 14 just above the ashpit and upwardly extending side chambers or recesses 15 are formed in the fire-box wall, the chambers or recesses 50 having restricted side openings extending throughout their length and communicating with the fire-box chamber and unrestricted top openings having in horizontal section a circular body and a communicating

passage therefrom to the fire. These chambers extend through the upper end of the wall and permit air to be carried around the body of fuel in order to insure the completion of combustion within the dome. From 60 the upper end of the dome a flue 16 extends into a suitable chimney or other draft connection (not shown). The stove has a combustion chamber enclosed by a jacket which depends about the fire box. This jacket 65 consists in the present instance of four wall members constituting front, two sides and back respectively. On the drawings these wall members are designated by reference character 18 designating the front wall member, the two side members by reference character 19 and the rear wall member by reference character 22. The front and the two sides are connected together to a single unitary construction prior to the assembly of 70 the wall members about the combustion chamber by stove bolts 20 taking through registering openings 21 in the front wall member and in lugs 21' extending out from the edges of the side wall members. A remaining part of the jacket is formed of a 75 rear wall 22. The side members 19 are provided with lugs 24 which engage companion lugs 25 of the combustion chamber, in the present instance on the dome part of the chamber, in such manner as to permit the front part of the jacket to be slid into and out of assembled position. Three lugs 23 and 24 are provided on the inner surface of each side wall 19, two of the lugs 24 being 80 above and at the sides of the other lug 23. These lugs form between them a way in which may be inserted an elongated lug 25 on each side of the dome. A single lug 26 is formed in the present instance on the inner 85 face of the front wall 18 of the jacket, and this lug is adapted to engage under a lug or rib 27 at the top of the fire-box. The rear part or wall 22 is provided upon its inner face with inwardly extending lugs 28 and 90 29 arranged like the lugs 23 and 24 respectively. These lugs slide onto and under an elongated lug 31 at the back of the combustion chamber, in the present instance being 95 a part of the flange 32 at the top of the fire-box. When it is desired to assemble a stove embodying my invention the front part is 100 slid into position horizontally from the front and the back then slid in similarly from the rear and the two parts fastened to 105 110 115

gether along their adjacent vertical edges 33 through suitable bolts or screws. The rear wall is of course cut away to provide an opening 34 through which the flue 16 may 5 extend. A suitable cap 35 is positioned over the top of the jacket and if desired this cap may be surmounted by a second cap 36.

On the drawing the vent openings for the issuance of the heated air from the stove are 10 not shown, and it will be understood that they may be provided at any desired locality in any desired arrangement.

It is thought that the invention and many of its attendant advantages will be understood from the foregoing description, and it will be apparent that various changes may be made in the form, construction and arrangement of the parts without departing from the spirit and scope of the invention 20 or sacrificing all of its material advantages, the form hereinbefore described being merely a preferred embodiment thereof.

I claim:

1. In a stove, the combination of an internal construction providing an ashpit,

firebox and combustion chamber, and an external open bottom jacket, said internal construction being of circular cross-section and said jacket being of rectangular cross-section, said jacket being supported from the 30 internal construction and at adjacent points of its rectangular section with the circular section of the internal construction, whereby free inlet of air between the internal construction and the jacket at the jacket bottom is provided.

2. In a stove, the combination of an internal construction providing an ashpit, firebox and combustion chamber, and an external open bottom jacket, said internal construction being of circular cross-section, said jacket being supported from the internal construction and at adjacent points of its circular section with the rectangular section of the jacket, said points being located well 40 above the bottom of the jacket, whereby free inlet of air between the internal construction 45 of the jacket at the jacket bottom is provided.

LEWIS MOORE.
